PLAYPEN

Thore Eriksson, Malins Hill, and Eric Nilsson, Lekaryds-vagen 68, both of Alvesta, Sweden

Filed Feb. 27, 1968, Ser. No. 10,745

Term of patent 14 years

Int. Cl. D6—01

U.S. Cl. D5—5

FIG.2

FIG. 1 is a perspective view of a playpen, showing our new design; and

FIG. 2 is a fragmentary view thereof showing the upper portion of a coupling means in an open position.

The playpen is circular in top plan.

We claim:

The ornamental design for a playpen, as shown and described.
